CIRCUIT-ARRANGEMENT IN AN AUTOMATIC SIGNALING SYSTEM FOR THE NUMERICAL ADJUSTMENT OF A FINAL SELECTOR UNDER THE CONTROL OF PULSES

Robert Berthold Buchner, Hilversum, Netherlands, assignor to Hartford National Bank and Trust Company, Hartford, Conn., as trustee

Application October 5, 1950, Serial No. 188,535

Claims priority, application Netherlands October 7, 1949

4 Claims. (Cl. 179—18)

The invention relates to a circuit-arrangement in an automatic signalling system, for example, an automatic telephone system, for the numerical adjustment of a final single-motion selector of fixed rest position under the control of pulses.

It has heretofore been suggested to provide a circuit-arrangement for the adjustment of a switch constituted by two groups of individual marking contacts, that is to say contacts not connected to similar contacts of another switch, contacts of one group being arranged between contacts of the other group. Under the control of dial pulses, a pulse contact alternately supplies a start indication and a stop indication alternately to the contacts of one group and those of the other group, any further contacts having a start indication. The control-device of the switch tests, by way of a testing arm, the character of the indication. The control device arrests the switch when the test arm reaches a marking contact which has a stop indication, and it causes the switch to continue its movement when the marking contact reached has a start indication.

In the rest position of the selector the breaking contact has a stop indication. At the beginning of the first pulse the indications are interchanged and the selector moves on until a marking contact of the other group having a stop indication is reached. At the end of the first pulse, the pulse contact again interchanges the indications, so that the contact at which the selector was arrested assumes a start indication and the selector moves on until a contact of the other group is reached which now has a stop indication. Hence the arrangement operates as an electric escapement.

The stop indication may be constituted, for example, by the presence of voltage across the marking contact, whereas a contact with start indication has no voltage and is thus not connected to a source of voltage, or conversely, the stop indication may be constituted by the absence of voltage and the start indication by the presence of voltage.

This method has the advantage that single-motion switches may be used, which are simpler and cheaper than switches of bi-dimensional motion, registers or separate adjusting switches being dispensed with. Since the spacings between the contacts at which the selector is arrested at the end of a pulse series may be varied within wide limits according to circumstances, the numerical groups may be of widely different size.

The principle involved may be applied not only to the adjustment of group selectors but also to that of final selectors. However, the known circuit-arrangement makes use of it for the adjustment to a desired tens. During the adjustment to the desired outlet within the tens, the switch operates as a stop switch, so that the arrangement cannot be used for any centrally driven switches.

Switches which are adapted to operate as stop switches with self-interrupting contacts have the disadvantage that the speed cannot be increased to a sufficiently high extent, so that the reliability of the adjustment is seriously affected.

The invention mitigates these disadvantages and provides a circuit-arrangement in which both the tens adjustment and the adjustment to the desired outlet are effected with the use of an electric escapement.

The invention is characterized in that the groups of contacts associated with the same tens are divided into

2

two main groups and the contacts of each tens of the first main group are arranged between contacts of a decade of the second main group. The pulse contact member, during a unit pulse series, supplies a stop indication and a start indication alternately to the contacts of one main group and those of the other main group such that at the adjustment to a contact of the main group during the unit pulses, the contacts of this main group exhibit the start indication.

10 The principle of the known method for adjusting a switch with the use of an electric escapement will be described in detail with reference to Fig. 1 of the accompanying drawing.

Fig. 2 shows one embodiment of a circuit-arrangement according to the invention.

Fig. 1 shows a number of marking contacts 1 to 10 of a switch, which are contacted by the same test wiper T. In the rest position of the switch, the wiper T engages contact 1. The contacts having odd numbers are connected to a common line L₁ while the contacts having even numbers are connected to a line L₂. The winding of rotary magnet D of the switch is arranged intermediate the wiper T and a terminal of a battery B_a, the other terminal of which is connected to earth potential. In the rest position, the pulse member a connects the line L₂ to earth across its break contact. The rotary magnet D is then not energized and the switch is not in motion.

At the beginning of the first pulse, a pulse relay (not shown) moves the pulse member a to connect to the left, with the result that the contacts of odd numbers are connected to earth, that is to say, they assume the start indication. The rotary magnet D is thus energized in a circuit passing from earth, across the make contact of a line L₁, marking contact 1, test wiper T, the winding of the rotary magnet D to the battery B_a, thereby actuating the switch. The unnumbered contacts arranged between the numerical contacts are connected to earth, so that when a test wiper strikes one of these contacts the rotary magnet remains energized and the switch moves on until a contact not connected to earth, that is to say, a contact exhibiting a stop indication, is reached. This, in the present case, is contact 2. The switch remains on this contact till at the end of the pulse the pulse member a is moved back to the rest position. The rotary magnet D is then re-energized and the switch moves to the next contact exhibiting a stop indication, that is to say, contact 3. The next pulse moves the switch from contact 3 via contact 4 to contact 5, and so forth. The contacts having odd numbers are consequently the contacts to which the switch can be numerically adjusted at the end of a pulse series.

It is obvious that the contacts having even numbers, which act as intermediate stop contacts, are required to prevent the switch from reaching a contact having an odd number before the pulse has ended and this contact reassumes the stop indication.

It may now occur that the spacing between a contact having an odd number and the next following contact having an even number is so large that the pulse has expired before the switch has reached the contact having an even number. In this case the switch does not stop at this contact because it again exhibits the start indication. This is not inconvenient per se since the selector switch moves on. However, care should be taken to see that the speed of the switch is such that the intermediate stop contact is passed before it has again supplied to it the stop indication at the beginning of the next following pulse.

70 A similar condition may prevail, if the switch reaches a contact having an odd number at an instant when a next following selection pulse has already started.

In the final selector circuit shown in Fig. 2, only those elements are indicated which are required for understanding the invention.

Of the contact bank of the selector only part of the escapement arc is shown. Arranged at the side of the break contact N are two non-numerical contacts V₁ and V₂, the corresponding outlets of which have no outlet lines connected to them. The contacts 11, 12 and so

forth, associated with the first tens are spaced apart by a distance of two contacts. The intermediate contacts 21, 22 and so forth are contacts of the second decade. After the contacts of the first two tens, the contacts of the third and the fourth tens are alternately arranged in a similar manner.

The contacts are engaged by the test wiper T of the final selector, D again designating the rotary magnet. The contacts N, V₂, 29, 20 and so forth are connected through line L₁ and break contact O² of the relay O to the break contact of the pulse contact a² of the pulse relay. The contacts V₁, 10 and so forth are connected through line L₄ and break contact O¹ to the make contact tact of the pulse contact a².

In the energized condition of relay B, the contacts 11, 31 and so forth are connected through make contact b² of this relay also the line L₄ and the break contact O¹ to the make contact a².

During the tens pulse series, the contacts 21, 22, 23 and so forth are connected through line L₂ and break contact e² of the relay E to earth and during the unit pulse series they are connected through make contact e² to the line L₁.

Similarly, during the tens pulse series, the contacts 12, 13, 14 and so forth are connected through break contact e³ of the relay E to earth and during the unit pulse series through make contact e³ to the line L₄.

The circuit-arrangement operates as follows:

When the final selector is engaged by a group selector in the preceding stage, the busy relay C is energized through lead L₆, the rotary magnet D not being excited, since the make contact b¹ is still open.

The dial pulses are supplied to the pulse relay A. At the beginning of the first pulse of the tens series, relay A becomes operative and closes through its make contact a¹ an energizing circuit for relay B. This relay is a slow-releasing relay so that it is held energized for the entire pulse series and is de-energized some time after the termination of the last pulse.

Since the make-contact b¹ closes after relay A has changed over the armature a², the energizing circuit for the rotary magnet D is not completed during the first pulse and the selector remains in its rest position.

At the end of the first tens pulse the armature a² returns to its rest position, so that a circuit is completed from earth through break contact a², break contact O², line L₁, break contact N, test wiper T, make contact b¹, make contact c¹, and the winding of rotary magnet D to battery B_a.

The rotary magnet D is energized in this circuit. The selector leaves the break contact N, but stops immediately at the next following contact, because this contact is now not connected to earth.

If a second pulse of the tens series does not follow, relay B is de-energized, so that relay E is energized in a circuit from earth through winding of relay E, break contact b³, off-normal contact k² of the selector, and make contact c² to battery B_a. Relay E completes a holding circuit for itself through make contact e¹, independent of break contact b³ and connects the contacts 21, 22 and so forth, through a make contact e², to the line L₁ and through a make contact e³, the contacts 12, 13 and so forth to the line L₄.

The circuit remains in this condition until the beginning of the first pulse of the unit series. Owing to the energization of relay A, relay B is re-energized through a make contact a¹, and is held energized for the unit pulse series.

Owing to the closure of make contact a² contact V₁ assumes the start indication, so that the test wiper leaves contact V₁. As contact V₂ is reached the energizing circuit of D is interrupted and the selector stops. At the end of the first unit pulse the indications are again interchanged and the test wiper moves to contact 11, that is to say, the first contact of the first tens, which now exhibits the stop indication.

At the beginning of the second unit pulse, a circuit is completed from earth through make contact a², break contact O¹, line L₄, make contact b², line L₅, marking contact 11, brush T, make contact b¹, make contact c¹, and the winding of rotary magnet D to battery. The selector then moves to contact 21. This contact is connected to earth at the end of the second pulse through break contact a², so that the rotary magnet D is re-energized and the selector moves to contact 12.

The selector is moved in a similar manner by the third unit pulse to contact 13. The contact V₁ acts as a preliminary contact for the first tens, that is to say, if the selector of the first pulse of the decade series stops at this contact, the selector moves after the first unit pulse to the first contact 11, associated with the first tens.

The tens pulse series will now be assumed to be formed by two pulses. As described above, the selector is moved to contact V₁ by the first tens pulse. Since after a definite time the first pulse is followed by a second, the relay B is held energized. The second tens pulse then moves the selector from contact V₁ to contact 11 in exactly the same manner as did the first unit pulse in the preceding case, that is to say, the selector stops at contact V₂ during the first pulse and at the end of the pulse moves to contact 11. Contact 11 is the preliminary contact of the second tens.

Since a third tens pulse does not follow, relay B is de-energized, so that, as in the preceding case, after the tens pulse series relay E is energized. Now a circuit is completed from battery B_a through break contact b², line L₅, marking contact 11, brush T, break contact b¹, and winding O₁ of relay O to earth. Relay O is energized in this circuit and completes a holding circuit for itself through its make contact O³ and a second winding O₂.

The change-over contact O¹ and O² commutate the pulse member a² with respect to the lines L₁ and L₄.

This does not result in the energization of rotary magnet D, since the circuit is broken at break contact b¹.

Obviously the pulse member a² may be commutated in a different manner, for example, with the use of a counting circuit in the selector or in the register, which commutes the pulse member after an even series of decade pulses.

At the beginning of the first pulse of the then following unit series relay A becomes operative, so that contact a² switches the earth connection from the line L₄ to the line L₁. Relay B is energized through make contact a¹ and is held energized for the duration of the unit series.

Now a circuit is completed from the battery through the winding of D, make contact C¹, make contact b¹, brush T, marking contact 11, line L₅, and make contact b² to line L₄. However, the rotary magnet is not energized, because the pulse member a² removes the earth connection from line L₄ before the make contacts of relay B are closed.

At the end of the first unit pulse, the pulse member a² reverts to its rest position, so that the line L₄ is connected to earth through make contact O¹ and break contact a². The selector thus moves to contact 21.

It should be noted that the first pulse shifts the selector relatively to one contact only.

The second unit pulse shifts the selector to contact 22, the third pulse to contact 23, and so forth, in a manner exactly similar to that described above.

If the tens pulse series is formed by three pulses, the first two pulses move the selector to contact 11. Upon passing this contact, relay O is not energized, since relay B is held energized.

At the beginning of the third pulse, contact 11 is earthed. The selector leaves this contact and passes by the contacts 12 to 19 and 21 to 28, since they are connected to earth through break contacts e² and e³. When the selector reaches contact 29 before the pulse has ceased, it stops at this contact and moves towards contact 10 on at the end of the pulse.

Contact 10 is the preliminary contact for the third tens. The adjustment to the unit within this tens is effected in a manner exactly similar to that within the first tens.

The fourth tens pulse moves the selector to contact 31, the preliminary contact of the fourth tens, whence the adjustment to the desired outlet takes place similarly to the second decade.

In a similar manner contact 30 is the preliminary contact of the fifth tens and contact 51 the preliminary contact of the sixth tens, and so forth.

After the selector is adjusted to a desired outlet, a test is made in a known manner, not described here in greater detail, whether the outlet is free or engaged.

At the end of the call, relay C is de-energized, so that rotary magnet D is energized in the circuit of battery B_a, rotary magnet D, break contact C¹, and off-normal contact K¹ of the selector to earth, and the selector moves until in the rest position contact K¹ opens.

It is obvious that within the scope of the invention the circuit-arrangement may be varied in a number of

ways; thus, for example, the start indication may be constituted by non-connection of a marking contact to earth or to a battery, while the contacts having a stop indication are connected to earth or to a battery. If desired, further contacts may be arranged between the decade contacts shown, for example, non numerical contacts and contacts of outlets to which P. B. X-lines are connected.

What I claim is:

1. In an automatic signalling system, a circuit arrangement responsive to pulses of a tens pulse series and of a unit pulse series for the numerical adjustment of a final single-motion selector of fixed rest position, said selector having a test wiper and first and second groups of individual contacts, each of said groups having a subgroup representing the same tens, the contacts of the first group being disposed between the contacts of the second group, the contacts of said first and second groups being respectively designated as preliminary and intermediate contacts, said circuit arrangement comprising a pulse contact member for supplying during the periods between the beginning and end of a tens pulse series a stop indication to said preliminary contacts and a start indication to said intermediate contacts, said pulse member during a unit pulse series supplying alternately a stop indication and a start indication to the subgroup of the first group and the subgroup of the second group, commutation means coupled between said member and said first and second groups to interchange the indications supplied to said preliminary and intermediate contacts at the beginning and end of each tens pulse series, and a control device coupled to said selector and including means to actuate said test wiper, said control device further including means responsive to said indications to arrest said actuating means when the test wiper reaches a contact having a stop indication and to actuate said actuating means to cause said selector to move on when the test wiper reaches a contact having a start indication.

2. A circuit arrangement as set forth in claim 1 fur-

ther including means causing the pulse contact member during a unit pulse to supply a start indication to the subgroup of the first group when after a decade pulse series the selector has been arrested and its test wiper has reached a contact of the subgroup of the first group, and wherein said commutation means includes means to commutate said member when the selector has been arrested and its test wiper has reached a contact of the subgroup of the second group.

10 3. A circuit arrangement as set forth in claim 2 wherein said commutation means includes a relay and means to actuate said relay during the tens pulse series and to deactivate said relay after the tens pulse series.

15 4. A circuit arrangement as set forth in claim 3 wherein the preliminary contacts which have a stop indication during a unit pulse are arranged in the contact bank immediately before the first contact of the subgroup of the first group and wherein the control device includes means to arrest the selector when said relay is deactivated.
